CLAIM

The ornamental design for a control needle, as shown and described.

DESCRIPTION

FIG. 1 is a first isometric view of a first embodiment of a control needle;

FIG. 2 is a second isometric view of the first embodiment of the control needle;

FIG. 3 is a third isometric view of the first embodiment of the control needle;

FIG. 4 is a top side view of the first embodiment of the control needle;

A bottom side of the first embodiment of the control needle is a mirror image of the top side;

FIG. 5 is a left side view of the first embodiment of the control needle;

A right side of the first embodiment of the control needle is a mirror image of the left side;

FIG. 6 is a front elevational view of the first embodiment of the control needle; and,

FIG. 7 is a rear elevational view of the first embodiment of the control needle.

The broken lines shown represent portions of a control needle and form no part of the claimed design.
